UNITED STATES PATENT OFFICE.

RUDOLF BERENDES AND WILHELM GRÜTTEFIEN, OF ELBERFELD, GERMANY, AS
SIGNORS TO FARBFENFABRIKEN VORM. FRIEDR. BAYER AND CO., OF LEVERKUSEN,
NEAR COLOGNE, GERMANY.

TABLET.

No Drawing.

Application filed June 15, 1922. Serial No. 568,627.

To all whom it may concern:

Be it known that we, RUDOLF BERENDES and WILHELM GRÜTTEFIEN, citizens of Germany, residing at Elberfeld, Prussia, Germany, have invented new and useful Improvements in Tablets, of which the following is a specification.

This invention relates to new tablets of valuable antipyretic and antineuritic properties. They enable the physician to obtain the action of salicylates without unpleasant or injurious by-effects. The new tablets contain as an essential ingredient the acetyl-meta-cresotinic acid having the formula

Owing to its insolubility in the gastric juice it is devoid of the irritating effect of the salicylates in the stomach. In the alkaline intestinal juices it liberates meta-cresotinic acid which shows a far less diaphoretic action than the salicylic acid liberated from acetyl-salicylic acid. Our new tablets contain acetyl-meta-cresotinic acid and other ingredients such as starch.

In order that the tablets may be used directly, the tablets of the present invention are advantageously prepared with a definite amount of acetyl-meta-cresotinic acid and we have found that tablets containing 0.5 gram are particularly valuable. Not only is easy and accurate dosage thereby made possible, but such tablets contain what we have found to be a proper and normal amount of the acetyl-meta-cresotinic acid. Moreover by breaking such tablets in half, which is made possible by their hard but brittle structure, doses of 0.25 gram are readily obtained, while for larger doses 2 or 3 tablets can be used. The tablets are readily disintegrated in water, either warm or cold, and are advantageously so disintegrated in water, either warm or cold, and are advantageously so disintegrated before taking.

We have now made the surprising dis-

covery that the acetyl-meta-cresotinic acid has the above stated therapeutically valuable properties and that this material is particularly valuable as a remedy. The material itself, the acetyl-meta-cresotinic acid, has been known as a chemical product. The use of this material as a therapeutic compound has never heretofore been proposed. The acetyl-meta-cresotinic acid is prepared by treating e.g. 250 parts by weight of meta-cresotinic acid with 400 parts by weight of acetic acid anhydride and 2 parts by weight of pyridine. This mixture is allowed to stay at the ordinary temperature. After some time the product separates. It is filtered off and crystallized from benzene. It melts at about 139° C.

We claim:—

1. As a new article of manufacture and an antipyretic, antineuritic tablet comprising acetyl-meta-cresotinic acid.
2. As a new article of manufacture and an antipyretic, antineuritic tablet containing about 0.5 gram of acetyl-meta-cresotinic acid.
3. As a new article of manufacture, a hard compressed whitish antipyretic and antineuritic tablet comprising acetyl-meta-cresotinic acid which disintegrates in water.
4. As a new article of manufacture and an antipyretic, antineuritic tablet comprising acetyl-meta-cresotinic acid which is tasteless and disintegrates in water.
5. As a new article of manufacture, a hard brittle antipyretic and antineuritic tablet comprising acetyl-meta-cresotinic acid.
6. As a new article of manufacture, a hard brittle whitish antipyretic and antineuritic tablet containing about 0.5 gram of acetyl-meta-cresotinic acid, said tablet being substantially free from foreign substances, and readily disintegrating in water.

In testimony whereof we have hereunto set our hands.

RUDOLF BERENDES.
WILHELM GRÜTTEFIEN.
